UNITED STATES PATENT OFFICE.

LEON B. STODDARD, OF WILLIMANSETT, MASSACHUSETTS.

RAZOR-BLADE-STROPPING DEVICE.

Application filed February 8, 1924. Serial No. 691,408.

To all whom it may concern:

Be it known that I, LEON B. STODDARD, a citizen of the United States, residing at Willimansett, in the county of Hampden and 5 State of Massachusetts, have invented certain new and useful Improvements in Razor-Blade-Stropping Devices, of which the following is a specification.

This invention relates to razor blade 10 stropping devices, and has particular reference to an improved device for facilitating the stropping of razor blades, and particularly safety razor blades.

The primary object of the invention is 15 to provide a device of the above kind which is simple and durable in construction and efficient in operation.

Another object of the invention is to provide simple and effective means for causing 20 the blade to be shifted laterally as it is drawn longitudinally of the razor strop in either direction, whereby the blade is given a path of movement oblique to the longitudinal axis of the strop during the stropping 25 operation, so as to insure a most effective stropping of the blade.

Another object of the invention is to generally simplify and improve the construction 30 of devices of the above kind, whereby the same may be manufactured and marketed at a relatively low cost to provide a readily and easily operable efficient device of this kind.

Other objects will appear as the nature 35 of the invention is better understood, and the same consists in the novel form, combination and arrangement of parts herein-after more fully described, shown in the accompanying drawings and claimed.

In the drawings, wherein like reference 40 characters indicate corresponding parts throughout the several views,

Figure 1 is a front elevational view of a stropping device constructed in accordance 45 with the present invention and showing the blade and blade holder intermediate their operative positions, the strop being indicated in position as shown in transverse section,

Figure 2 is a side elevational view of the device shown in Figure 1 illustrating the 50 position of parts when the blade is drawn in one direction and engaged with the strop,

Figure 3 is a view similar to Figure 2 55 with the blade shifted and drawn in the opposite direction,

Figure 4 is an enlarged fragmentary view partly in longitudinal section and partly in elevation, of the device shown in Figure 1.

Figure 5 is a view similar to Figure 2 60 but partly in longitudinal section,

Figure 6 is a perspective view showing the blade holder yoke and its stationary jaw,

Figure 7 is a perspective view of the adjustable jaw and its adjusting screw, and 65

Figure 8 is a diagrammatic plan view illustrating the movements given to the blade during the stropping operation.

Referring more in detail to the drawings, 70 the present invention includes a separable handle 5 having its exterior suitably roughened and provided with a screw-threaded socket in its inner end for reception of the screw 6 centrally secured to the handle

yoke 7 whereby the yoke and handle are 75 separably connected, it being however apparent that other forms of connection may be employed. The handle yoke 7 is provided with transversely alined openings 8 in the inner portions of the legs thereof, and these

openings are elongated longitudinally of the legs of the yoke 7 for a purpose which will presently become apparent. Loosely disposed in the openings 8 of the yoke 7 is 80 a rock shaft 9, one end of which is formed with a crank 10 having an elongated end portion 11 and disposed adjacent to the outer side of one of the legs of the yoke 7 as shown clearly in Figures 1 and 4. A

suitable roller 12 is secured upon the rock 85 shaft 9 by means of a transverse pin 13 or the like, and this roller is substantially of a length to extend from one leg to the other of the yoke 7.

The invention further includes a blade 90 holder embodying a yoke formed of a tubular intermediate portion 14 that is longitudinally slotted at its outer side as

at 15 and which includes a short leg 16 and a relatively long leg 17, respectively disposed outwardly of and spaced from the

legs of the handle yoke 7. The free end of the leg 16 and the inner portion of the leg 17 are provided with alined openings 18 in which are secured the ends of a screw

shaft 19, and this shaft 19 is slidably and 100 pivotally disposed in openings provided in transverse alinement within the outer ends of the legs of the handle yoke 7. The

longest leg 17 of the blade holder yoke is 110 provided at its free end portion with a longitudinally elongated slot 20 in which the

end portion 11 of the crank 10 slidably and pivotally extends.

A second roller 21 is provided between the legs of the handle yoke 7 and is internally threaded for engagement with the threaded portion 22 of the shaft 19 so that upon restraining the shaft 19 from rotation and causing rotation of roller 21, the blade holder and the shaft 19 will be shifted transversely, with respect to the strop 23 that is adapted to be inserted between the rollers 12 and 21. A spring 24 is centrally secured upon the intermediate portion of the handle yoke 7 and has its free ends bearing against the shaft 9 at the end of the roller 12 for causing the latter to be yieldingly forced against the under-side of the strop 23, which is permitted by the elongated slots 8.

The blade holder preferably includes a jaw 25 the inner end portion of which is suitably rigidly secured within the tubular portion 14 of the blade holder yoke adjacent one end of the latter, and a second jaw 26 the inner end of which is slidably disposed within the tubular portion 14 and which has the inner end of an adjusting screw 27 swivelled therein as at 28, the adjusting screw 27 having threaded engagement with the opposite end of the tubular portion 14 of the blade holder yoke. The jaws 25 and 26 project outwardly through the slot 15 of the tubular member 14 and have their adjacent free end portions suitably formed or grooved as at 29 for engagement with the side edges of the razor blade 30 to be stropped.

In operation the adjusting screw 27 is threaded outwardly of the handle yoke member 14 so as to draw the movable jaw 26 away from the stationary jaw 25 a sufficient distance to permit the blade 30 to be inserted. The blade 30 is disposed with its back portion within the slot 15 and then the screw 27 is operated to cause the blade to be clamped at its side edges between the jaws 25 and 26 as shown clearly in Figure 4. The strop is then directed between the rollers 12 and 21, and upon exerting a pull upon the handle 5 in one direction as indicated by the arrow *a* in Figure 2, the roller 12 will be caused to rotate so as to swing the crank 10 and thereby cause the blade holder to be swung so as to bring the blade 30 downwardly into engagement with the strop in a direction opposite to that in which the stropping device is pulled. As soon as the edge of the blade comes in contact with the upper surface of the strop 23, due to the friction of the roller 12 upon the strop, the roller 12 is prevented from rotation and is thereby caused to slide along the under surface of the strop, but continued rotation of the roller 21 is permitted. Due to the fact that shaft 19 is held from rota-

tion the rotation of the roller 21 will cause the shaft 19 to be fed uniformly and slowly transversely of the device and strop as diagrammatically indicated in Figure 8, until the leg 17 of the blade holder yoke 70 engages the adjacent portion of the crank 10, at which time this stroke is completed and the handle pulled in the opposite direction as indicated by the arrow *b* in Figure 3. When the handle is pulled in the direction of the arrow *b*, the operation is reversed so as to cause the blade to be shifted transversely of the strop in the opposite direction. It is well known that this compound movement effects a most desirable stropping of the blade.

From the foregoing description it is believed that the construction and operation as well as the advantages of the present invention will be readily understood and appreciated by those skilled in the art.

What I claim as new is:

1. In a razor blade stropping device, a handle, a yoke centrally attached to the handle, a screw shaft journalled in the yoke and slidably disposed therein, a blade holder including a yoke fixed to the ends of said screw shaft, a roller disposed within the handle yoke and threaded upon the screw shaft whereby the latter may be shifted transversely of the handle, a rock shaft disposed inwardly of the screw shaft and journalled in the handle yoke, a second roller fixed upon said rock shaft, and operative connections between the rock shaft and the yoke of the blade holder for causing the latter to swing in the opposite direction in which the handle is drawn.

2. In a razor blade stropping device, a handle, a yoke centrally attached to the handle, a screw shaft journalled in the yoke and slidably disposed therein, a blade holder including a yoke fixed to the ends of said screw shaft, a roller disposed within the handle yoke and threaded upon the screw shaft whereby the latter may be shifted transversely of the handle, a rock shaft disposed inwardly of the screw shaft and journalled in the handle yoke, a second roller fixed upon said rock shaft, operative connections between the rock shaft and the yoke of the blade holder for causing the latter to swing in the opposite direction in which the handle is drawn, and blade holding means including a stationary jaw and an adjustable jaw carried by the blade holder yoke.

3. In a razor blade stropping device, a handle, a yoke centrally attached to the handle, a screw shaft journalled in the yoke and slidably disposed therein, a blade holder including a yoke fixed to the ends of said screw shaft, a roller disposed within the handle yoke and threaded upon the screw shaft whereby the latter may be shifted transversely of the handle, a rock shaft dis-

- posed inwardly of the screw shaft and journaled in the handle yoke, a second roller fixed upon said rock shaft, operative connections between the rock shaft and the yoke of the blade holder for causing the latter to swing in the opposite direction in which the handle is drawn, the operative connection between the rock shaft and the blade holder yoke comprising a crank upon one end of the rock shaft, and an elongated leg having a longitudinal slot in which the crank is loosely and pivotally disposed, said elongated leg forming part of the blade holding yoke.
4. In a razor blade stropping device, a handle, a yoke centrally attached to the handle, a screw shaft journalled in the yoke and slidably disposed therein, a blade holder including a yoke fixed to the ends of said

screw shaft, a roller disposed within the handle yoke and threaded upon the screw shaft whereby the latter may be shifted transversely of the handle, a rock shaft disposed inwardly of the screw shaft and journaled in the handle yoke, a second roller fixed upon said rock shaft, operative connections between the rock shaft and the yoke of the blade holder for causing the latter to swing in the opposite direction in which the handle is drawn, said rock shaft being shiftable toward and away from the screw shaft, and yieldable means carried by the handle yoke for normally urging said rock shaft and the roller carried thereby toward the screw shaft.

In testimony whereof I affix my signature.

LEON B. STODDARD.
